UNITED STATES PATENT OFFICE.

CARL DAHLSTEDT, OF ROCKFORD, ILLINOIS.

VALVE-GRINDER.

1,338,212.

Specification of Letters Patent. Patented Apr. 27, 1920.

Application filed December 23, 1918. Serial No. 267,988.

To all whom it may concern:

Be it known that I, CARL DAHLSTEDT, a citizen of the United States, residing at Rockford, in the county of Winnebago and State of Illinois, have invented certain new and useful Improvements in Valve-Grinders, of which the following is a specification.

This invention pertains to devices for grinding valves on their seats for the purpose of securing a true and tight seating of the valves. This practice of regrinding the lift valves of motor vehicles is well known; but the matter of properly grinding the valves to remove carbon deposits and scoring or pitting so that the valves will seat tight and true, is difficult to accomplish, especially by one inexperienced in the handling of machine tools or metal working.

The chief object of the present invention is to provide a simple and inexpensive means permitting an inexperienced person to properly grind a valve, and to this end my invention consists, generally stated, in the provision of a suitable hand crank or handle adapted to connect with a valve head for rotating the same, means for yieldingly and constantly urging the valve against its seat, and of means for intermittently lifting the valve from and returning it to its seat while it is being manually rotated by the hand crank.

I have also aimed to provide a valve-grinding device of the character described, in which a valve will be lifted from and returned to its seat at irregular intervals during the grinding without interruption of the valve turning operation, this being accomplished preferably by a simple device arranged on the valve push rod and actuated by one hand while the other is employed to turn the valve.

Other objects and attendant advantages will be appreciated as the invention becomes better understood by reference to the following description when considered in connection with the accompanying drawings, in which--

Figure 1 is a vertical sectional view through the head of an engine showing a valve grinder in connection therewith embodying my improvements;

Fig. 2, a detail view in perspective of one of the parts employed for lifting the valve; and

Fig. 3, a plan sectional view taken on the line 3-3 of Fig. 1.

In the present instance, I have, simply for

the purpose of illustration, shown my improvements in connection with an internal combustion engine of the type in which the cylinder head 5 is provided with a threaded opening 6 above and in alignment with the valve. As shown in the drawing, the valve head 7 seats on a seat 8 and is provided with the usual stem or push rod 9 slideable vertically in a suitable bearing 11 and depending at its lower end within a roller bearing 12 in which is guided the lower end of the push rod, not shown, which is actuated by the cam.

In order to properly grind a valve of this character a suitable mixture of ground glass and oil, or other abrasive is sparingly applied to the bevel face of the valve, and the latter when in position on the valve seat is rotated back and forth about a quarter of a turn or more, then lifted slightly from the seat and the position changed and then replaced and the operation repeated until the bearing surface is smooth and bright. It is this operation that I have aimed to perform without the necessity of manually lifting the valve from its seat or from appreciatively interrupting the rotation of the valve.

With the foregoing in mind, I have provided a manually rotatable member in the form of a suitable crank 13 adapted for connection at its lower end with the head of a valve, preferably by means of a blade 14 entering a slot 15 in the top of the valve head. The crank 13 is supported in working position by a block or cap 16 threadingly engaged in the opening 6, the crank rod passing through a central opening in the cap. An expansion spring 17 interposed between an abutment 18 on the lower end of the crank rod and the underwall of the cap constantly urges the crank rod downwardly when the supporting cap 16 is tightened in the position shown in Fig. 1, and consequently urges the valve down against its seat. It will be manifest that with a construction of the character described the valve will be continually pressed against its seat while being rotated by the crank 13 and that this downward pressure is automatically imposed by the spring 17 and not by manual pressure.

It is now desired to lift the valve and return it to its seat at irregular intervals in accordance with the above mentioned method which is recognized as being most practical for obtaining the best results. For this purpose, I have provided a collar 19

adapted to be suitably secured as by means of a set screw 21, to the lower portion of the push rod 9 just above the bearing 12 and in coöperative relation with a disk 22, 5 which rests on the top of the bearing 12. This disk is free to rotate with and independently of the push rod 9, and I have provided means operative between the collar 19 and disk 22 for causing these parts 10 to rotate together and for causing the push rod to be lifted at predetermined intervals by holding the disk against rotation. This is effected in a simple manner by equipping one of the parts, for example the collar 15 19, with one or more depending lugs 23 and providing the other part with a plurality of depressions 24 suitably arranged and in which the lugs 23 are adapted to enter. As shown in Fig. 1, when these lugs 23 are 20 located in the depressions 24 the valve will be seated and the collar 19 is arranged so as not to interfere with the above mentioned function of the spring. It will be manifest that when the crank 13 is rotated all of the 25 parts connected with the valve stem will turn in unison and that when it is desired to lift the valve from its seat to change its position for the purpose mentioned above, the operator who is turning the crank with 30 one hand, uses the other to momentarily hold the disk 22 stationary. This causes the lugs 23 to rise out of the depressions 24, thereby lifting the valve from its seat against the tension of the spring 17. According 35 to the present arrangement of the lugs 23 and depressions 24 the valve will be held raised for approximately a half revolution or until the lugs again enter the recesses, whereupon the disk 22 is released. 40 As shown in Fig. 3, the depressions 24 might be quarteringly arranged, and it will be understood that by manipulating the disk 22 while the crank is being turned the valve may be raised and lowered at irregular intervals 45 to secure the desired interrupted movements and changed position of the valve.

While I have illustrated and described a single working embodiment of my improvement, it should be understood that various changes might be made in the construction and arrangement without departing from the spirit and scope of the invention as expressed in the appended claims: in which- 50

55 I claim:

1. A valve grinder comprising a manually rotatable member adapted for connection with a valve for imparting rotary movement thereto, means for yieldingly and constantly urging the valve against its seat, and means 60 adapted to be manually actuated independently of said rotatable member for causing the valve to be lifted at will from and returned to its seat while being rotated by 65 said member.

2. In an engine valve grinder of the character described the combination of means for rotating a valve, means for constantly yieldingly urging the valve against its seat, means operative between the lower portion 70 of the valve push rod and an adjacent stationary part for intermittently lifting the valve from its seat, said valve-lifting means comprising a part fixed to the valve push rod, a part rotatable with and independently 75 of said push rod, and means operative between said parts for causing the first mentioned part to be lifted against the pressure of said yielding means when the second mentioned part is held against rotation. 80

3. In an engine valve grinder of the character described, the combination of means for rotating a valve, means for yieldingly urging the valve against its seat, and means operative between the lower portion of the 85 valve push rod and an adjacent stationary part of the engine for intermittently lifting the valve from its seat, at will and causing, during the periods between said lifting movement, the valve to be rotated against 90 its seat.

4. A valve grinder of the character described comprising a member adapted to be threadingly engaged in connection with a cylinder head, a rotatable member passing 95 through said threaded member and adapted to connect with a valve head for rotating the same, a spring operative between the rotatable and threaded members for urging the rotatable member and the valve which 100 it engages downwardly to press the valve against its seat, and means for causing the valve to be intermittently lifted from and returned to its seat while the valve is being rotated. 105

5. A valve grinder comprising in combination with a threaded opening in the cylinder head above a valve, of a cap threadingly engaged in said opening, a member co-axial with the valve and passing through said cap 110 and detachably engageable with the valve for rotating the same, said member movable rotatably and lengthwise of its axis with respect to said cap, an expansion spring interposed between the cap and said member 115 for urging the latter in a direction to force the valve against its seat, and means adapted to be actuated independently of operation of said rotatable member for causing the valve and said member to be lifted intermittently during rotation of the valve. 120

6. A valve grinder, comprising means operating on the head of the valve for imparting rotary motion thereto, means for yieldingly urging the valve against its seat, 125 and means coöperative between the valve rod and a part of the engine for lifting the valve at will at variably different times during rotation of the valve.

CARL DAHLSTEDT.
